(57) **CLAIM**

The ornamental design for a fishing reel line roller, as shown and described.

DESCRIPTION

FIG. 1 is a perspective view of a fishing reel line roller showing the new design;

FIG. 2 is a front view of the fishing reel line roller of FIG. 1 showing the new design;

FIG. 3 is a plan view of the fishing reel line roller of FIG. 1 showing the new design;

FIG. 4 is a right side view of the fishing reel line roller of FIG. 1 showing the new design;

FIG. 5 is a left side view of the fishing reel line roller of FIG. 1 showing the new design;

FIG. 6 is a 6-6 line cross-sectional view of the fishing reel line roller of FIG. 3 showing the new design; and,

FIG. 7 is a side view of the fishing reel line roller of FIG. 1 in an environment of use.

The broken lines in the drawings depict environmental structure and portions of the fishing reel line roller that form no part of the claim.

1 Claim, 7 Drawing Sheets
